UNITED STATES PATENT OFFICE

DONALD S. BARROWS, OF ROCHESTER, NEW YORK

ORGAN STOP OR COUPLER ACTUATING MEANS

Application filed December 1, 1930. Serial No. 499,351.

The invention relates to control devices for pipe organs and has special reference to a stop key for drawing on or throwing off stops or couplers.

5 The principal object of the invention generally stated, is to provide stop keys of such form and construction that they may be moved to the on or off position by the same directional movement of the fingers of the player's hand, that is to say, simply by the application of pressure directly either upon the face of an upward projecting portion or upon a lower key or tongue portion, without its being necessary, although possible, to apply a lifting pressure from beneath said tongue portion.

It is well known that the stop or coupler actuating means of an organ were commonly constructed in the form of draw knobs. Obviously a draw knob requires two distinct movements. It must be pulled out to draw on the stop or coupler, and pushed back to throw off the stop or coupler. A later development is in the form of generally rectangular tilting tablets, pivotally mounted at their centers, so that by the application of pressure at the bottom or top, they may be tilted forward or backward and thereby draw on or throw off the stop or coupler mechanisms of which they are respectively a part. These simple tablets however, although in extensive use as coupler actuating means, possess certain disadvantages in that their regular surfaces do not indicate to the sense of touch the portion of the tablet which the player desires to press, and that the player's fingers may inadvertently slip off. Tablets have been made with terminal ridges at top and bottom and also with longitudinal grooves, but that

10 neither of these features alone or in combination meet the requirements of the player is evidenced by the obsolescence of these variants from the straight face tablet. Likewise the increased use of straight projecting stop keys or tongues over that of the draw knobs and plain tablets indicates the defects of the latter two.

It is with the above facts in view that I have devised the present invention which

15 pipe organs and has special reference to a stop key for drawing on or throwing off stops or couplers. design or form of stop key which may be roughly described either as a conventional stop key having an added upper projection portion adapted to throw the key into the off position by simple pressure thereon, or as a tablet having an angularly formed face, so that the respective inclinations of the lower and upper portions are at normal and convenient angles to the direction of movement of the player's fingers when throwing the tablet or key into the on or off positions respectively, thereby avoiding the danger of the fingers slipping off as above set forth, and providing further a central portion which affords to the sense of touch a definite division or demarcation between the on and off pressure surfaces of the face, thereby contributing greatly to the accuracy and speed of the player's movements.

20 Another important and characteristic feature of my invention lies in the fact that with keys or tablets formed in accordance therewith, the player may, by a single movement of the hand, simultaneously throw some keys into their on positions and other keys into their off positions, the individual pressure faces being in each case at the most convenient angle and most nearly normal to the general direction of movement of the player's hand.

25 The exact type or method of mounting my improved key or tablet is immaterial, as this depends upon the type of mechanism to be operated, but it may be mounted as simply and as inexpensively as any other. It is also as well adapted as any other to operate any type of usually related mechanism, and to be itself operated, or moved in position, by any of the usual combination actuating means.

30 It therefore combines with several novel and useful features, low cost of manufacture, efficiency and durability in service, positive action and universal adaptability in mounting and in operation. It is therefore a general improvement in the art.

35 To the attainment of the foregoing and other objects and advantages, the invention preferably consists in the details of construction and the arrangement and combination

of parts to be hereinafter more fully described and claimed, and illustrated in the accompanying drawings in which:

5 Figure 1 is a perspective view showing a plurality of the stop keys or tablets with the performer's hand in the act of making changes in the registration.

10 Figure 2 is a vertical sectional view giving a side elevation of one of the keys or tablets and illustrating one type of operating mechanism connected therewith.

15 Figure 3 is a similar view showing a slightly modified form of key or tablet, particularly in so far as its mounting is concerned, and disclosing it as adapted for combinational actuation by bellows or pneumatics of the pressure type.

20 Figure 4 is a fragmentary view showing the tail of the key or tablet when it is to be operated or moved through combinational action by pneumatics of the suction or exhaust type.

25 Figure 5 is a detail sectional view showing the tail of the key as forming a circuit closer or a part of a switch for electrical operation of stop or coupler action.

30 Figure 6 is a vertical sectional view showing one of many ways of arranging the key or tablet to operate stop or coupler action pneumatically instead of electrically.

35 Referring more particularly to the drawings, and especially Figure 1 it will be observed that I have disclosed a series of stop keys or tablets 10 constructed in accordance with my invention. These keys are located at the usual place on an organ console and are intended to take the place of and perform the same functions as the ordinary type of knob, key or tablet, in that they control the actuation of stop or coupler mechanism, and optionally and additionally, the setting or pre-arrangement of registration combinations and may in turn be actuated or moved by any of the various well known types of combination mechanism. In Figures 1 and 2 each of these keys or tablets 10 is represented as comprising a single angular body member or key 11 having an upwardly projecting portion 13 and pivoted at 12 for vertical 40 swinging movement. When the body 11 is described as angular, it is meant that there are two actuating or pressure receiving surfaces 13 and 14 at an angle to each other, it being considered immaterial exactly how the 45 key is mechanically constructed so as to bring about this desired condition. The key may be built up into the desired form from two or more parts permanently or removably secured together in any convenient manner. 50 The surface 13 is at the upper end of the body or above the pivot 12 whereas the surface 14 is below the pivot and it is therefore apparent that all it requires to move the key in the two possible directions is a simple pressure 55 applied either above or below the pivot,

thereby making it possible for a performer to move or shift any desired number of such keys or tablets either into the off or on position by the same general motion of the fingers, this quite logically reducing the effort required and consequently speeding up the changing of registration. Actually the key or tablet is represented as having its face concaved at 15, the curve of the concavity merging into the lower actuating surface 14 and ending at the surface 13, the idea being that a performer under the necessity of making hurried changes in registration may do so by subconsciously locating the desired pressure surfaces by their relation to the central concavity 15.

70 Figure 2 shows the upper arm or end of the key or tablet as having pivotally connected therewith, at 16, a push and pull rod 17 leading to whatever mechanism is to be controlled, it being considered unnecessary to provide any thorough showing thereof.

75 In Figure 3 I have illustrated a slightly different form of key or tablet 18, in so far as its mounting and operation are concerned. 80 In this modification the key is shown as simply notched at 19 for rocking engagement upon a rod or pintle 20. Furthermore instead of the push and pull rod 17 there is disclosed a "tail" 21 or rod which projects rearwardly from the key and which extends between a pair of pneumatics or bellows 22 of the compression type. When the key 18 and tail 21 are respectively in the positions shown in full lines, air under pressure admitted through the combination mechanism into lower bellows 22 expands same, thereby forcing tail 21 up and key 18 down into the on position, as indicated by dot and dash lines. Conversely pressure air similarly admitted into upper bellows 22 will force down tail 21 and restore key 18 to the off position. A bow spring 23 is provided and operates to maintain the key or tablet 18 in either of its selected positions, one of which is shown by full lines and the other by dot and dash lines. 90 Clearly, there is no restriction as to the embodiment of the invention in a control system in which the pneumatics are of the compression type, and in Figure 4 there is illustrated a variation in which the tail 24, corresponding to the tail 21 and operated in the same manner, is moved by the horns or arms 25 on bellows or pneumatics 26 of the suction or exhaust type. It is obvious that any 95 convenient actuating means may be used to effect key movement in connection with combinational changes in registration, and that the rear portion of the key may be formed for direct or indirect actuation by pressure, exhaust, electromagnets or mechanical means. I therefore do not limit the use of my invention to any particular auxiliary mechanism, whether mentioned or illustrated herein or not.

Figure 5 shows a common method of utilizing the metallic tail of the key as a switch or circuit closer for primary electrical actuation of stop, coupler or other organ mechanism. It is obvious that any convenient portion of the key may be thus utilized.

In Figure 6 I have also shown one of the many methods whereby the key may operate stop, coupler or other organ mechanism pneumatically, by providing that the key may in its two positions alternately uncover and close an air port such as 29, thereby actuating certain other pneumatic mechanism.

While I have shown and described a number of alternative constructions or mountings of the key and several different types of devices to be actuated thereby, or which may operate said key, and a certain definite shape of the active face of the key itself, it should be understood that the disclosure is merely an exemplification of the general underlying or fundamental features and that I reserve the right to make all such changes in the details as will not depart from the spirit of the invention or the scope of the claims hereunto appended.

Having thus described the invention, I claim:

1. An organ control element having finger pressure receiving surfaces located at an angle with respect to each other.
2. An organ control element mounted for pivotal movement and provided at opposite sides of its pivot with finger pressure receiving surfaces arranged at an angle with respect to each other.
3. A pivoted organ control element provided at its upper and lower end portions with pressure receiving surfaces at opposite sides of a substantially central concavity.
4. An organ control element comprising a pivotally mounted body member having its face concaved to define spaced pressure receiving surfaces arranged at an angle to each other.
5. An organ control element comprising a pivotally mounted body member formed substantially centrally with a curved concavity and provided at opposite sides thereof and adjacent its ends with flat surfaces arranged at an angle to each other and adapted to have pressure applied thereto.
6. An organ control key having a plurality of angularly related finger pressure receiving surfaces whereby to be movable in a selected one of a plurality of directions by the same character of movement.
7. An organ console stop key comprising a pivotally mounted body formed at opposite sides of a plane passing through the pivot with angularly related finger pressure receiving surfaces.
8. An organ console stop key comprising a pivotally mounted body formed at opposite sides of a plane passing through the pivot

with angularly related finger pressure receiving surfaces arranged in outwardly diverging relation.

In testimony whereof I affix my signature.

DONALD S. BARROWS.
